UNITED STATES PATENT OFFICE.

JOSEPH U. GEROW, OF BROOKLYN, NEW YORK.

DESIGN FOR WATCH-CHAIN CHARM.

Specification forming part of Design No. **11,540**, dated December 16, 1879; application filed February 3, 1879.
[Term of patent 3½ years.]

To all whom it may concern:

Be it known that I, JOSEPH U. GEROW, of the city of Brooklyn, in the county of Kings and State of New York, have originated a Design for a Watch-Chain Charm, of which the following is a full, clear, and exact description, reference being had to the accompanying drawings, making part of this specification.

This design is intended to be of a small size, adapted to hang on the watch-chain.

In the drawings it is in a magnified size for greater clearness.

Figure 1 is a side view, and Fig. 2 is an end view.

The handle B is cylindrical. At one end is the ring d. The miniature hammer A is at the other end of the handle. Said hammer has an offset at 1, between the square portion 2 of the head and the curved portion 3, which is

split into two portions, as seen in Fig. 2. The angles at 4 are removed to form an octagonal end.

The design of this ornamental head is neat and attractive, and, with the handle and ring, forms a watch-chain charm.

The pencil-case and pencil within the handle are represented as extended in Fig. 1.

I claim as my invention—

The design of the watch-chain charm, as described and represented, the same consisting of a tubular handle and a ring at one end and an imitation hammer-head at the other end, with the square central portion, 2, the offset at 1, the curved split portion 3, and the octagonal end 4, as described and shown.

JOSEPH U. GEROW.
